UNITED STATES PATENT OFFICE.

FRANK H. CUTSFORTH, OF GERVAIS, OREGON.

MOWING-MACHINE.

1,179,702.

Specification of Letters Patent. Patented Apr. 18, 1916.

Application filed September 7, 1915. Serial No. 49,357.

To all whom it may concern:

Be it known that I, FRANK H. CUTSFORTH, a citizen of the United States, residing at Gervais, county of Marion, State of Oregon, have invented certain new and useful Improvements in Mowing-Machines, of which the following is a specification.

My invention relates to machines for mowing hay, grain, and the like, and particularly to certain improvements in a vertical cutter-bar at the outer end of the horizontal cutter-bar.

The objections to such vertical cutters heretofore have been that they easily clog up with the stalks of the grass or grain being cut, and that their use necessitates the removal of the shoe upon the outer end of the horizontal cutter and the installation of a special shoe for use with the vertical cutter, and the replacement of the original shoe when the vertical cutter is removed.

I overcome the above objections by means of the construction described herein and illustrated in the accompanying drawings, which form a part of this application for Letters Patent, and in which—

Figure 1 is a perspective view of a portion of a horizontal cutter-bar with a vertical cutter-bar attached thereto embodying my invention. Fig. 2 is a side elevation of a part of the shoe and the vertical cutter-bars. Fig. 3 is a section on line AA of Fig. 2. Fig. 4 is a plan view of the shoe. Fig. 5 is a perspective view of the side plate of the shoe. Fig. 6 is a detailed side elevation of one of the vertical cutter-bars. Fig. 7 is a rear elevation of the vertical cutter-bars and their mounting. Fig. 8 is a perspective view of the cover used to close the opening in the shoe when the vertical cutter-bars are removed.

Like characters of reference indicate like parts throughout the several views, in which, numeral 1 is the horizontal cutter-bar, 2 the fingers, and 3 the rod as well known and generally constructed in the art. A recess 4 is provided in the shoe for receiving the bar 3, the bar and the shoe being secured together by bolts. The rod or post 5, supporting the vertical cutter-bars, is mounted in a dovetailed recess 6 in the shoe, and secured therein by a bolt 6^a. A side plate 7 is provided for the shoe and secured thereto by bolt 6^a and screw 8. A longitudinal orifice 9 is formed intermediate said plate and the shoe, into which orifice the lower end of cut-

ter-bar 16 enters upon its downward stroke. As cutter 16 enters said orifice the grass or grain is sheared between the lower cutting edge 10 of said cutter and the upper edge 11 of the plate 7. A cutter 12 is inserted into plate 7 and is adapted to contact with the vertical cutter-bar 16 as same enters longitudinal orifice 9. Extending forward from the lower end of one of vertical cutter-bars 16 is a finger 13 having an inclined upper edge 14, said edge extending rearwardly and terminating adjacent the lower diagonal cutting edge 15 of the cutter-bar, as shown in Figs. 1, 2 and 6. A co-acting cutter-bar 17 contacts with cutter-bar 16, the cutting edges of the said cutter-bars being alternately spaced, as shown in Figs. 1 and 2, and thus adapted to cut or shear the grass or grain as said cutter-bars reciprocate. Cutter-bar 17 does not enter longitudinal orifice 9 between the shoe and plate 7.

With the cutter-bars in the position shown on full lines in Figs. 1 and 2, any grass or grain that may be caught upon the shoe will be directed by the upper edge 14 of finger 13 between the cutting edges 15 and 18 of cutter-bars 16 and 17 respectively, and thus said grass or grain will be cut and will not clog the cutters. With cutter-bar 16 raised as shown in dotted lines in Fig. 2, any grass or grain caught upon the shoe will be directed along the shoe between same and the lower cutting edge 10 of cutter-bar 16, and will be cut as said cutter-bar enters orifice 9 upon the downward stroke thereof. It is thus evident that no clogging up of the cutter-bars by reason of uncut grass lodging between said cutter-bars and the shoe is possible. A guide arm 19 is bolted to post 5 and extended forward and upward for the purpose of guiding tall grass downward toward the vertical cutter-bars 16 and 17.

To prevent clogging at the upper ends of cutter-bars 16 and 17 by reason of any tall grass remaining uncut and falling over upon the upper ends of said cutter-bars or the operating mechanism thereof, I provide a rearwardly extending upwardly projecting extension or elongation 20 of arm 19, adapted to be substantially above and adjacent to the vertical cutter-bars.

For the purpose of imparting a reciprocating motion to cutter-bars 16 and 17, there is pivotally mounted upon the rear of post 5 a triple armed bell-crank 21, having two

arms extending substantially horizontally and one arm depending substantially vertically as shown in Fig. 7. Reach-rods 22 connect the horizontal arms of said bell-crank 21 with the upper ends of the cutter-bars 16 and 17, said rods being pivotally connected at each end thereof. A pitman 22^a is pivotally connected to the vertical arm of bell-crank 21, and extending through an orifice 23 in the shoe, connects to any convenient reciprocating member of the mower, as bar 3, said connection being made in any convenient manner.

When it is desired to remove the vertical cutter-bars, and use only the horizontal cutters, as for low grass or the like, bolt 6^a is removed and pitman 22 disconnected from bar 3, and thereupon post 5 may be readily lifted out of dovetailed socket 6 in the shoe and removed with all attachments thereto as a unit.

To fill longitudinal orifice 9 after the removal of the vertical cutter-bars, I provide a cover 23^a formed to fit said orifice, having a downwardly turned finger 24 adapted to enter orifice 9 at the extreme forward point thereof, a dovetailed shaped portion 25 adapted to enter the dovetailed socket 6 in the shoe, and a downwardly extending flange 26 having an orifice 27 therein adapted to receive bolt 6^a.

My invention may be made of any size and constructed of any material deemed convenient and suitable in a device of this character, and while I have illustrated and described a preferred construction and arrangement of parts considered desirable in materializing my invention, I wish to in-

clude in this application for Letters Patent, all mechanical equivalents or substitutes 40 that may fairly be considered to come within the scope and purview of my invention, as defined by the appended claims.

Having thus disclosed my invention, what I claim is:—

1. In a mowing machine, a horizontal cutter-arm, a shoe mounted upon the outward end of said arm, said shoe having a dovetailed socket therein, a vertical standard adapted to be secured within said dovetailed socket, 50 vertical reciprocating cutter-bars mounted upon said standard, a forwardly extending finger upon one of said vertical cutter-bars, a side plate secured to the outer face of said shoe and adapted to form a longitudinal orifice therebetween, said orifice being in the plane of said finger and adapted to allow said finger to enter therein, a forwardly extending upwardly projecting guide-arm mounted upon said standard, and a rearwardly extending upwardly projecting elongation of said arm.

2. In a mowing machine having vertically reciprocating cutter-bars, and a shoe having a longitudinal orifice therein substantially in the plane of one of said cutter-bars, a forwardly extending finger integral with one of said cutter-bars adapted to enter said orifice.

In witness whereof I claim the foregoing as my own, I hereunto affix my signature in the presence of two subscribing witnesses.

FRANK H. CUTSFORTH.
